URINAL SCREEN

Louis Clark, Los Angeles, Calif., assignor to Clark Paper Converting Corp., Los Angeles, Calif., a corporation of California

Filed June 5, 1962, Ser. No. 70,425

Term of patent 14 years

(Cl. D4—5)

FIG. 1 is a top plan view of a urinal screen showing my new design.

FIGURE 2 is a front edge elevation thereof, looking from the top toward the bottom or narrow edge thereof.

FIGURE 3 is a side elevation looking from the right toward the left.

FIGURE 4 is a bottom plan view.

FIG. 5 is a cross-sectional view taken on the line 5—5 of FIG. 1.

I claim:

The ornamental design for a urinal screen, as shown.
